Attorney.

UNITED STATES PATENT OFFICE.

HANS HENRIK BLACHE, OF HELLERUP, NEAR COPENHAGEN, DENMARK.

FASTENING-STUD FOR EXHAUST-VALVES IN INTERNAL-COMBUSTION ENGINES.

1,332,316.

Specification of Letters Patent.

Patented Mar. 2, 1920.

Application filed September 18, 1919. Serial No. 324,682.

To all whom it may concern:

Be it known that I, HANS HENRIK BLACHE, citizen of the Kingdom of Denmark, residing at 32 Sofievej, Hellerup, near Copenhagen, Denmark, have invented certain new and useful Improvements in Fastening-Studs for Exhaust-Valves in Internal-Combustion Engines, of which the following is a specification.

10 In internal-combustion engines, the exhaust valves have heretofore been located in a cylindrically turned casing inserted in a corresponding bore in the cover, it being forced against a seat in the cover by means of threaded studs passing through a projection in the valve casing. This construction was subject to the drawback that the valve casing, when expanding more than the cylinder cover on account of being heated 15 by the combustion gases driven through the casing, either might rupture the studs or become broken itself by the lugs on the casing being torn off.

20 The present invention removes this drawback by the provision, below the nuts of the studs or the like which fasten the valve casing to the cylinder cover and which are made longer than otherwise necessary for tightening the parts together, of long sleeves 25 or the like encircling the studs, or being disposed in some other manner below the nuts, these sleeves being made of a freely expandible material able to resist compression, for instance cast iron. According to the 30 invention, the studs are turned down or reduced in diameter for a considerable distance below the thread, so that the strain on the studs will mainly act on the long portion of the studs, and also the cast iron 35 sleeves are turned down or reduced in diameter, so that their cross-section will not be larger than necessary on account of the strength, the result being attained that the device will act like a powerful spring allowing 40 the valve casing to expand without being overstrained.

On the drawing there is illustrated a valve casing containing the exhaust-valve for a four-stroke-cycle internal-combustion engine.

An exhaust valve such as the one shown is subject to highly varying expansion on account of the heat of the combustion gases, which will cause the casing to be heated far 50 more than the cylinder cover, which is cooled by the circulating cooling water. On

the drawing, *a* indicates the valve casing, while *b* is the valve proper. *c* indicates the cylinder cover having an opening or socket wherein the valve casing is inserted, the 60 casing with its shoulder *d* fitting tightly against the cylinder cover *c*. *e* are the two studs, where the valve casing is tightened against the cylinder cover by means of the nuts *f*. According to the invention, the 65 studs *e* are made longer than would be necessary for the purpose of tightening and, below the nuts *f*, there are inserted the elastic or freely expandible members or sleeves *g*, whose lengths correspond to the lengthened portion of the studs *e*. The stud *e* is turned down, generally for the entire distance between the upper thread for the nut *f* and the lower thread by which the stud is screwed down into the cover. The sleeves 70 are also turned down for nearly their entire length. The said reduction of the diameter of the studs causes the strain on the studs to be concentrated on the reduced portion. The studs and the sleeves will 75 thereby be caused to act as powerful springs pressing the valve casing firmly against the cylinder cover.

I claim as my invention:

1. The combination, with a cylinder head 85 having a socket therein and a pair of threaded bolt holes at opposite sides of the socket; of a valve casing having a portion fitting in said socket and also having a pair of bolt holes which register with the first-named 90 holes; a pair of bolts inserted through the second-named holes and having their terminals threaded, the lower terminals of the bolts being secured in the first-named holes; a pair of elongated, freely expandible tubu- 95 lar members loosely encircling said bolts and resting at their lower ends upon the valve casing but terminating short of the threaded upper terminals of the bolts; and a pair of nuts threaded upon said upper 100 terminals and tightened against the upper ends of said tubular members, the inner walls of the sleeves and the walls of the bolt holes in the valve casing being spaced from the surfaces of the bolts to permit the 105 free expansion of said sleeves, whereby the latter are caused to impose pressure upon said casing so as to force it against the cylinder head.

2. The combination, with a cylinder head 110 having a socket therein and a pair of threaded bolt holes at opposite sides of the socket;

of a valve casing having a portion fitting in said socket and also having a pair of bolt holes which register with the first-named holes; a pair of bolts inserted through the second-named holes and having their terminals threaded, the lower terminals of the bolts being secured in the first-named holes; a pair of cast iron sleeves loosely encircling said bolts and resting at their lower ends upon the valve casing, but terminating short of the threaded upper terminals of the bolts; and a pair of nuts threaded upon said up-

per terminals and tightened against the upper ends of said sleeves, the intermediate portions of the bolts being reduced in diameter in order to space the surfaces of said portions from the inner walls of the sleeves and the walls of the bolt holes in the casing to permit the free expansion of said sleeves, whereby the latter are caused to impose pressure upon said casing so as to force it against the cylinder head.

In testimony whereof I affix my signature.

HANS HENRIK BLACHE.
